SURFACE TREATING MACHINE OR SIMILAR ARTICLE

Arthur M. Felske, Westport, and Robert J. Reading,
Darien, Conn., assignors to General Electric Company,
a corporation of New York

Application February 7, 1956, Serial No. 40,064

Term of patent 14 years

(Cl. D9—2)

Fig. 2.

Fig. 3.

Fig. 4.

Fig. 1 is a perspective view of a surface treating machine or similar article embodying our new design and showing the front, top and one side thereof;

Fig. 2 is a perspective view thereof showing the back, top and other side;

Fig. 3 is a top plan view thereof, and

Fig. 4 is a side elevation view thereof.

The dominant features of the design reside in the portions shown in full lines. Only a portion of the handle is shown.

We claim:

The ornamental design for a surface treating machine or similar article, substantially as shown and described.
